Charles E. Godley,

Edward N. Pagsen.

Attorney

UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

LAMP.

Application filed March 31, 1923. Serial No. 628,997.

To all whom it may concern:

Be it known that I, CHARLES E. GODLEY, a citizen of the United States, and residing at Detroit, in the county of Wayne and State 5 of Michigan, have invented a new and Improved Lamp, of which the following is a specification.

The particular object of this invention is to produce lamps which shall have minimum 10 height or longitudinal measurement for their diameter or transverse measurement and therefore be acceptable as ceiling or wall lights for omnibuses and other enclosed vehicles. A further object of this invention is 15 to provide a lamp of this character which shall have the least number of parts and which can be assembled with the least amount of work and at low cost.

In the accompanying drawing, Fig. 1 is a 20 side elevation of this improved lamp. Fig. 2 is a section on the line 2—2 of Fig. 1. Fig. 3 is a section of the reflector on the line 3—3 of Fig. 4. Fig. 4 is a front elevation of the reflector and the light bulb mounted therein 25 and Fig. 5 is a detail view of the connector bar.

Similar reference characters refer to like parts throughout the several views.

This lamp is built up of a lens ring, a lens, 30 a reflector, a connector bar which positions the reflector relative to the lens, a packing ring and a spring.

The lens ring is a ribbon 1 of metal having a rib 2 at one edge to stiffen it and 35 formed with a second rib 3 by grooving the other edge to receive the edge of the lens 4, this ribbon being bent to constitute a cylinder.

The ends of the ribbon 1 may be formed 40 with tongues 5, each of which overlaps the opposite end of the ribbon. Buttons 6 may be secured to the ends of this ribbon and a spring 7 engages these buttons and presses them toward each other, thereby causing the 45 lens ring to grip the lens.

The cup-shaped reflector 9 is secured to the middle portion of the transverse connector bar 10 in any desired manner, rivets 11 being shown. The ends 12 of the bar 10 50 are bent at right angles and carry the screws 13 which are adapted to slide in the bayonet

slots 14 in the lens ring. In doing so they draw the lens ring toward the connector bar and the lens toward the flange 15 at the edge of the reflector, the packing ring 16 being 55 interposed to secure a dust-proof joint between the reflector and lens.

The connector sleeve 18 is mounted in the reflector and is at such an angle that the filament of the bulb 19 is at one side of the 60 focus of the reflector. This results in a diffused beam being projected at an angle to the axis of the reflector and the dimensions and directions of such beams can be varied as desired by those skilled in this art by 65 changing this angle and location of the connector sleeve. The lamp may be secured in position by means of screws passing through the holes 20 in the inclined portions 22 of the connector bar and I prefer to cut away 70 corners of the ends 12, as shown in Fig. 5, to give easy access to these holes 20. After the bar 10 is in position, the lens ring can be attached thereto.

The details and proportions of the several 75 parts of this lamp may be all varied by those skilled in the art without departing from the spirit of my invention as set forth in the following claims.

I claim:

1. In a lamp, the combination of a bar, a cup-shaped reflector attached to the middle portion thereof, a lens to close the open end of the reflector, and a lens ring attached at one end to the lens and at the other to the 80 ends of the bar.

2. In a lamp, the combination of a bar, a cup-shaped reflector centrally attached to the middle portion of the bar, a lens to close the open end of the reflector, and a lens ring attached to the lens and to the ends of said bar, said ring comprising a ribbon of metal and a spring to hold the ends thereof together, one edge of the ribbon being grooved to receive the edge of the lens. 85

3. In a lamp, the combination of a bar, a cup-shaped reflector attached to the middle portion thereof, a connector tube and light bulb mounted in the reflector and so positioned that the illuminating portion of the 90 filament of said bulb will be at one side of the focal axis of the reflector, a lens to

close the open end of the reflector, and a lens ring attached to the lens and to the ends of the bar.

4. In a lamp, the combination of a bar having its ends turned at right angles, a cup-shaped reflector attached to the middle portion of the bar, a lens to close the open

end of the reflector, pins extending in opposite directions from the outer sides of said turned ends of the bar, and a cylindrical lens holder attached at one end to the lens and having bayonet slots formed in its opposite end to receive the pins on said bar. ¹⁰

CHARLES E. GODLEY.
